UNITED STATES PATENT OFFICE

2,599,947

PAPER COATING APPARATUS

Robert A. Sherman, Decatur, and Luther O. Carlisle, La Grange, Ill., assignors to A. E. Staley Manufacturing Company, Decatur, Ill., a corporation of Delaware

Application January 21, 1950, Serial No. 139,834

2 Claims. (Cl. 118—118)

1

This invention pertains to coating processes in general and specifically to an improved apparatus and method for applying compositions such as colored, starch-clay coatings to paper board.

The improvement is especially advantageous in the corrugated box board industry for the coloring of the liners. A common defect in such colored liners is that the final sheet shows a streaked or rippled pattern due to improper spreading of the coating on the liner. While this pattern may be desirable in special instances, it is ordinarily undesirable and is an indication of faulty application and/or apparatus. Another common defect in many coating operations is that excessive quantities of coating are unavoidably applied, with a consequent increased cost to the manufacturer.

Accordingly, the principal object of this invention is to provide an apparatus and method for coating paper giving a smooth, uniform coating of a controllable, predetermined thickness.

To the accomplishment of the foregoing and other related objects, the invention comprises the features hereinafter fully described, and particularly pointed out in the claims, the following description setting forth in detail a preferred, illustrative embodiment of the invention, exemplary, however, of but one of the various ways in which the principle of the invention may be employed.

The adaptation of the invention to the color coating of liners for corrugated boxboard will now be described, and illustrated in the accompanying drawings, in which:

Fig. 1 is a diagrammatic sketch of the overall coating operation.

Fig. 2 is an elevational view of a smoothing roll assembly embodying the invention.

Fig. 3 is an end view on line 3—3 of Fig. 2.

Referring now more particularly to the drawings, a wire-wrapped roll 4, performing the functions of spreading, smoothing, and metering the coating, is positioned just beyond the point where the coating composition is applied to the paper by the pump or gravity fed applicator 3. This roll, of the type shown in U. S. Patent 1,043,021, may be of a diameter of about $\frac{1}{2}$ to three inches, and is closely and tightly wrapped over most of its length, which is dependent upon the paper width, with a relatively fine wire. The wire diameter may be in a range such as to give anywhere from 10 to 120 wraps per inch but a size giving about 60-70 wraps per inch has been found very suitable. Rust-resistant and wear-resistant wire should be used, such as stainless steel or Nichrome wire.

2

The smoothing roll rests—or more aptly turns or “floats”—in a groove 5 of appropriate dimension running longitudinally along the hollow support roll 6, the diameter of which may be about three times that of the smoothing roll and which is rotatably held at either end in appropriate bearings, not shown. This support roll may conveniently have a plurality of grooves of different radii adapted to receive smoothing rolls of corresponding radii and wound with wires of various sizes. Coarser wire permits a heavier coating, other things being equal, because the larger V-shaped space between the wires permits more coating to remain on the paper.

15 The smoothing roll is held at either end in arms 7 fastened in locked position at the offset ends of the support roll by the bolts 8. Where a plurality of grooves are provided on the support roll, a corresponding plurality of such bolt-hole positions are likewise necessary.

20 One end 9 of the smoothing roll extends beyond the supporting arm to provide for the attachment of a conventional, variable speed, driving arrangement, not shown.

25 The smoothing roll does not touch the support roll. A layer of fabric or other pliant material 10 is placed between the two surfaces. Felt has been found to be very satisfactory for this purpose, and it is conveniently provided in the form of a cylinder so that it completely encircles the support roll. This material keeps the wire-wound roll clean as it is rotated in the groove in the direction opposite to the travel of the paper web. By moving this wrapper or cushion occasionally, a

30 new, clean surface is provided. The cleaning action obtained by this combination of reverse drive on the roll and the wrapper or cushion results in a greatly improved and uninterrupted coating operation, previously unobtainable in the industry.

35 In operation, a web of paper liner 1 from a feed roll or other source passes over one or more idle or guide rolls 2 and past an applicator device 3 for applying an excess of coating just ahead of the wire-wrapped smoothing roll 4. This roll spreads the coating uniformly, at a thickness depending in part upon the diameter of the wire used on the smoothing roll.

40 It is essential to the greatly improved performance of this smoothing roll that it be reversibly driven, with respect to the direction of paper movement. Furthermore, it is very desirable that a variable speed drive be used, to provide for variations in viscosity of the coating com-

position; otherwise, less accurate control of the coating film thickness results.

The paper then passes by way of idler rolls to a drying device 11, such as dryer rolls, before being rerolled.

Having described the invention, what is claimed as new is:

1. In apparatus for applying a liquid coating composition to a moving web, including means for feeding a web through the apparatus and means for applying a coating composition to the moving web, the combination comprising a wire-wrapped smoothing roll, means for reversibly driving said smoothing roll operatively connected therewith, means for supporting said roll in a smoothing relationship with said web, said smoothing roll support means including a stationary backing roll having a longitudinal recess in the surface thereof in which said smoothing roll is disposed so as to project therefrom; and a sheet of fabric material located in said recess and pressed between the opposing surfaces of said backing roll and said smoothing roll, said fabric

material serving as a wiper for the smoothing roll.

2. The apparatus of claim 1 wherein said fabric material is in the form of a sleeve surrounding said backing roll.
